(57) **CLAIM**

I claim the ornamental design for a bottom rubber socket for a walking stick, as shown and described.

DESCRIPTION

FIG. 1 is a perspective view of a bottom rubber socket for a walking stick of the present invention;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof;

FIG. 7 is a right side elevation view thereof; and,

FIG. 8 is a cross-sectional view thereof, taken in the direction of the arrows on the line 8—8 on FIG. 4.
